(57) **CLAIM**

The ornamental design for a support and storage box food processor, as shown and described.

DESCRIPTION

FIG. 1 is a perspective view of the support and storage box food processor, the main portion of the food processor supported over the box support portion; the storage blades and support shown in dashed line format and forming no part of the invention hereof;

FIG. 2 is a rear view;

FIG. 3 is a front view;

FIG. 4 is a right side view;

FIG. 5 is a left side view;

FIG. 6 is a top view; and

FIG. 7 is a bottom view; and,

FIG. 8 is a perspective view showing the box support portion in a position removed from the the main portion of the food processor and placed over the upper portion to form a covered storage configuration.
